CLAIM

I claim the ornamental design for a regenerative media filter with view window, as shown and described.

DESCRIPTION

FIG. 1 is a top plan view from the front of the filter;
 FIG. 2 is a left plan view of the filter;
 FIG. 3 is a front plan view of the filter;
 FIG. 4 is a right plan view of the filter;
 FIG. 5 is an isometric view from the front of the filter;
 FIG. 6 is a bottom plan view from the back of the filter;
 FIG. 7 is a top plan view from the back of the filter;
 FIG. 8 is a right plan view of the filter;
 FIG. 9 is a plan view from the back of the filter;
 FIG. 10 is a left plan view of the filter;
 FIG. 11 is an isometric view from the back of the filter; and,
 FIG. 12 is a bottom plan view from the back of the filter.
 The broken lines shown in the figures are for the purpose of illustrating portions of the regenerative media filter which form no part of the claimed design.

1 Claim, 12 Drawing Sheets
